[57] ABSTRACT

A discharge head for use in a fixed fire extinguishing system including a body member having an inlet and an outlet for receiving and discharging fire extinguishing agent, and a plug member normally retained in the body member by a latching assembly for preventing the flow of extinguishing agent through the body member. The latching assembly is adapted to release the plug member in response to a fire occurring in the vicinity of the body member, thus permitting the discharge of the plug member from its flow-preventing position. A fusible member cooperates with the plug and is adapted to fuse at a predetermined temperature to permit the flow of extinguishing agent through the body member independent of the operation of the latching assembly.

DISCHARGE HEAD FOR A FIXED FIRE EXTINGUISHING SYSTEM

BACKGROUND OF THE INVENTION

This invention relates to a discharge head, and more particularly to a discharge head adapted for use in a fixed fire extinguishing system.

Various types of discharge heads have been proposed for use in fixed fire extinguishing systems. The most common of these is a sprinkler head which incorporates a fusible member which is adapted to release a plug, or the like, in the head in response to a predetermined fire situation occurring in the vicinity of the head. The fusible member must be isolated from the plug due to the fact that the latter is in contact with the water, or other extinguishant, and is therefore at a temperature that is too low to permit effective operation of the fusible member if it were in a direct heat exchange relation with the plug. Therefore, a latching assembly is often employed to provide a connection between the plug and the fusible member to permit the latter to be isolated from the former. The latching assembly is adapted to release the plug upon collapse of the fusible member due to the heat of the fire and permit a discharge of the plug and a resultant discharge of extinguishant from the head.

However, these discharge heads suffer from the fact that, due to their relatively long periods of inaction, the latching assembly may become jammed, or otherwise inoperative, due to rust, dirt, grime, etc. collecting thereon. As a result, the entire head may be rendered inoperative despite the fact that the fusible member operates in a normal manner.

SUMMARY OF THE INVENTION

It is therefore an object of the present invention to provide a discharge head utilizing a latching assembly to connect a plug member to a fusible member, yet which is operable in the event the latching assembly becomes inoperative.

Towards the fulfillment of these and other objects, the discharge head of the present invention comprises a body member having an inlet for connecting to a source of extinguishant and an outlet for said extinguishant; a plug means disposed in said body member; latching means for latching said plug means in a position preventing the flow of extinguishant through said body member, said latching means being responsive to a predetermined fire condition in the vicinity of said body member for permitting the release of said plug means from its latched position and the resultant flow of extinguishant through said body member; and means cooperating with said plug means in said latched position for permitting the flow of extinguishant past said plug means in response to a fire condition different from said predetermined fire condition.

BRIEF DESCRIPTION OF THE DRAWINGS

Reference is now made to the accompanying drawings for a better understanding of the nature and objects of the present invention. The drawings illustrate the best mode presently contemplated for carrying out the objects of the invention and are not to be construed as restrictions or limitations on its scope. In the drawings:

FIG. 1 is a cross-sectional view of the discharge head of the present invention; and

FIG. 2 is an enlarged partial view of the discharge head of FIG. 1.

DESCRIPTION OF THE PREFERRED EMBODIMENTS

Referring to FIGS. 1 and 2, the discharge head of the present invention is shown in general by the reference numeral 10 and comprises a cylindrical body 12 having an upper end portion which is internally threaded as shown at 14 for connection to a source of extinguishant such as water, and a lower end portion which defines an outlet orifice 16 of a reduced cross-section. A pair of spiral vanes 18a and 18b are fixed within the body 12 for imparting a swirling motion to water flowing downwardly therethrough in a conventional manner. The vanes 18a and 18b support a hollow central hub 20 which, in turn, slidably supports a rod 22 having a head assembly 24 fixed on its lower end. The head assembly 24 operates to block the outlet orifice 16 and will be described in detail later.

The rod 22 is latched in the position shown in FIG. 1 by a latching assembly shown in general by the reference numeral 30 in FIG. 1. This assembly includes a rod 32 which slidably extends through an externally threaded boss 34 projecting from the side of the body 12. One end of the rod 32 extends through the vane 18a and the wall of the central hub 20 into a slot 36 in the rod 22 to latch it in the position shown in FIG. 1.

A sleeve 38 is threaded on the end of the boss 34. The outer end of the sleeve 38 is closed off by an externally threaded stub shaft 40 having a ring or yoke 42 thereon. The rod 32 slidably extends through the stub shaft 40, and the other end of the rod engages a conventional thermal fuse element 44 positioned within the ring 42. The fuse element 44 prevents movement of the rod 32 to the right as viewed in FIG. 1, until the heat of a fire fuses the element so that it collapses. Since the fuse element 44 is the standard type commonly used in conventional sprinkler heads now on the market, it will not be described in greater detail.

The rod 32 has a piston head 46 mounted thereon which slidably engages the internal wall of the sleeve 38. A spring 48 is positioned between the boss 34 and the piston head 46 to bias the piston head and the rod 32 to the right with a predetermined biasing force.

With this arrangement, the piston head 46 and the rod 32 will be driven to the right under the action of the spring 48 upon the fuse element 44 collapsing in response to the heat of the fire. This unlatches the rod 22 and allows it, along with the head assembly 24, to be expelled from the outlet orifice 16 of the body 12, and permit the water to spray out through the orifice.

It can be appreciated that the fusible member 44 is effectively isolated from the interior of the body 12, so that it will not be influenced by the moisture and low temperature conditions occurring therein due to the presence of the water.

The details of the head assembly 24 are shown better in FIG. 2. In particular, the head assembly includes a relatively thick-walled tubular member 50, the outer peripheral surface of which is spaced a small distance from the inner wall of the body 12. A pair of sealing rings 52 and 54 are disposed in annular grooves formed in the peripheral surface of the tubular member 50 and engage the inner wall of the body member 12. The rod 22 extends through the central bore of the tubular member 50, and an O-ring 56 is disposed in an annular

groove formed in the inner wall of the tubular member and engages the outer surface of the rod.

A sleeve 58 extends between the outer surface of the rod 22 and the inner wall of the tubular member 50, and flush with the bottom ends thereof, as viewed in FIG. 2. The sleeve 58 is formed of a fusible material that fuses at a higher temperature than the fusible link 44 of the latching assembly 30. As an example, the sleeve 58 may be adapted to fuse at 1,000°F., while the fusible link 44 may be selected to fuse at 286°F. In its non-fused condition, the sleeve 58 connects the tubular member 58 to the rod 22.

The discharge head 10 is incorporated in a fixed fire extinguishing system mounted at or near the ceiling of the structure to be protected from fire. In addition to several heads 10, the system will include a source of extinguishant and a network of pipes for supplying the extinguishant to the nozzles.

In operation, the presence of a fire below the discharge head 10 of a magnitude to produce heat which will fuse the link 44 will collapse the link and permit the spring 48 to force the rod 32 from its latching position with respect to the rod 22. As a result, the pressure of the water in the body 12 will force the plug assembly 24, and therefore the rod 22, outwardly from the body and thus permit a discharge of water from the outlet orifice 16. The vanes 18a and 18b will impart a swirling action to the water as it discharges from the body 12 in a conventional manner, resulting in a continuous conical discharge spray pattern.

In the event the mechanical linkage assembly 30 becomes jammed, or otherwise inoperative, due to the presence of foreign matter such as rust, dirt, or the like, the collapse of the link 44 will not cause discharge of the rod 22 and the plug assembly 24 from the body 12 and a resultant discharge of water. However, upon the temperature of the fire rising to the fusible temperature of the sleeve 58, the latter will melt and permit a release of the tubular member 50 from the rod 22. This results in a discharge of the member 50 through the outlet orifice 16 due to the pressure of the extinguishant in the body 12, and a resultant discharge of the water in a normal manner.

It can be appreciated that even if the rod 22 remains jammed in the body member 12 after release of the rod 32, the above discharge of water will be effected in response to the elevated temperature.

It is thus seen that the discharge head of the present invention is adapted for operation in a failsafe mode, which permits the automatic discharge of water therefrom despite a breakdown in its normal operating components.

Although the above operation has been described in connection with specific temperatures actuating the fusible link 44 and the fusible sleeve 58, it is understood that these temperatures can vary in accordance with particular design requirements.

Of course, other variations of the specific construction and arrangement of the discharge head disclosed above can be made by those skilled in the art without departing from the invention as defined in the appended claims.

I claim:

1. A discharge head for use in a fixed fire extinguishing system comprising a body member having an inlet for connecting to a source of extinguishant and an outlet for said extinguishant, a plug member extending in

said outlet, a rod connected to said plug member, control means responsive to a predetermined fire condition in the vicinity of said body member for permitting the release of said plug member from said outlet, and a fusible material connecting said plug member to said rod and adapted to fuse at a predetermined temperature to release said plug member from said rod and permit the discharge of extinguishant from said body member.

2. A discharge head for use in a fixed fire extinguishing system comprising a body member having an inlet for connecting to a source of extinguishant and an outlet for said extinguishant, a plug member extending in said outlet, a rod connected to said plug member, latching means for engaging said rod to latch said plug member in said outlet, control means cooperating with said latching means and responsive to a predetermined fire condition in the vicinity of said body member for permitting the release of said plug member from said outlet, and means for permitting the discharge of said extinguishant from said head in response to another fire condition different from said predetermined fire condition.

25 3. A discharge head for use in a fixed fire extinguishing system comprising a body member having an inlet for connecting to a source of extinguishant and an outlet for said extinguishant, a plug member extending in said outlet, a rod connected to said plug member, a fusible link, a spring loaded member connected to said link and said rod, said link being adapted to collapse in response to a predetermined fire condition in the vicinity of said body member for permitting said spring loaded member to disconnect from said rod and said plug member to release from said outlet, and means for 30 permitting the discharge of said extinguishant from said head in response to another fire condition different from said predetermined fire condition.

4. A discharge head for use in a fixed fire extinguishing system comprising a body member having an inlet 40 for connecting to a source of extinguishant and an outlet for said extinguishant; means for closing said outlet; first fire responsive means responsive to a first predetermined fire condition in the vicinity of said body member for opening said outlet; and second fire responsive means 45 responsive to a predetermined fire condition in the vicinity of said body member for opening said outlet.

5. The discharge head of claim 4 wherein said fire conditions are temperatures and wherein the temperature to which said second fire responsive means responds to is greater than the temperature to which said first fire responsive means responds to.

6. The discharge head of claim 4 wherein said second fire responsive means is adapted to open said outlet in the event said outlet is not opened by said first fire responsive means despite occurrence of said first predetermined fire condition.

7. The discharge head of claim 4 wherein said means for closing said outlet comprises a rod and a plug member connected to said rod and extending in said outlet.

65 8. The discharge head of claim 7 wherein said first fire responsive means comprises means for engaging said plug member in a manner to retain said plug member in said outlet and means responsive to said first predetermined fire condition for permitting a release of said engagement.

9. The discharge head of claim 7 wherein said first fire responsive means comprises latching means for engaging said rod to latch said plug member in said outlet, a fusible link, and a spring loaded member connected to said link and said rod, said link being adapted to collapse in response to said first predetermined fire situation to permit said spring loaded member to disconnect from said rod.

10. The discharge head of claim 7 wherein said second fire responsive means comprises a fusible material connecting said plug member to said rod and adapted to fuse at a predetermined temperature to release said plug member from said rod.

11. The discharge head of claim 4 wherein said

means for closing said outlet comprises plug means extending in said outlet and a link member adapted to retain said plug means in said outlet, said first and second fire responsive means each cooperating with said link member in a manner to permit release of said plug means from said outlet in response to said first predetermined fire condition and said predetermined fire condition, respectively.

12. The discharge head of claim 9 wherein said plug member is arranged and constructed to be expelled from the outlet by the pressure of extinguishant in said head when the plug member is released from said rod.
